FLUSH VALVE

Emil G. Oravec, Chicago, Ill., assignor to Crane
Co., Chicago, Ill., a corporation of Illinois

Application March 12, 1942, Serial No. 434,358

6 Claims. (Cl. 137—93)

This invention relates to a new and improved flush valve. More particularly, it has for one of its principal objects the provision of a novel construction in a silent operating valve which provides a silent refill.

A further important object of this invention is to provide a flush valve for closets having a spring loaded diaphragm wherein a novel arrangement of the diaphragm serves as a means for retarding the seating of the flush valve.

Another important object of this device lies in the provision of a continuously tapered disc of the serrated type which reduces turbulence or cavitation to a minimum and in combination with the seating regulator means insures proper refill for the closet bowl with which it is assembled, at the completion of each flushing operation.

A still further object of this invention is to provide a flush valve which may easily be adjusted for the automatic refill when installed with a variety of types or sizes of closet bowls.

Other and further important objects will be apparent from the disclosure in the specification and the accompanying drawings, in which

Fig. 1 is a vertical sectional assembly view of a flush valve embodying my invention.

Fig. 2 is a fragmentary sectional view showing the valve in closed position and as installed in a line carrying pressure.

Figs. 3, 4 and 5 illustrate successive positions of the valve diaphragm during respective flushing and refilling operations.

Fig. 6 shows a modified construction in which the employment of a bellows is substituted.

As shown in the drawings and referring to Fig. 1, the reference numeral 1 indicates generally the casing of a flush valve of this invention commonly employed in the flushing of closet bowls or the like and having an inlet port 2 and an outlet port 3. A tapered valve seat 4 is positioned in the casing 1 between the inlet 2 and the outlet 3, having in cooperation therewith the correspondingly tapered closure member 6 which preferably is a unitary part of the plunger member 7. The plunger member 7 comprises a body, an auxiliary or pilot valve 8 having a seat 9 and a spring 11 normally maintaining the pilot valve 8 in sealed relationship with its seat 9. An apertured passage or port 12 is provided in the side of the movable body, as indicated, having a central passageway 13, an annular cup leather 14 for guiding the plunger member and providing a peripheral sealing engagement within the casing 1 to accommodate the reciprocal movement of the closure

member 6 within the upper cylindrical chamber 16 through which the plunger member 7 travels when the closure member 6 is moved to and from its seat. At the upper end of this chamber 16 a diaphragm 17 is positioned and is held firmly in place by the threaded cap 18. The latter diaphragm 17 may be made of rubber or similar material. A supporting member or stiffening plate 19 is assembled with the diaphragm 17, as indicated; both the diaphragm 17 and the supporting member 19 are normally flexed in a convex shape by means of the coil spring 21 which is placed between the supporting member 19 and the cap 18. An adjusting screw 22 is threadedly mounted centrally within the cap 18 and acts directly against the spring 21 for either increasing or decreasing the tension thereof as desired. The cap 23 encloses the adjusting screw 22 to prevent any tampering with the valve adjustment.

The valve proper is provided with an actuating handle 24 tiltably mounted in the casing 1. Upon downward movement of the handle 24 the rod extension 26 contacts the stem 27 which is fixedly attached to the auxiliary valve 8. The latter movement of the handle causes the valve 8 to be canted or tilted from its seat 9, allowing line water confined within the chamber 16 to pass downwardly through the passageway 13, thence through the port normally intercepted by the auxiliary valve 8 and out through the bottom of the plunger 7. Immediately upon release of this fluid pressure in the chamber 16 the incoming line pressure commences to act against the leather cup 14 of the plunger 7, thus forcing the plunger to travel upwardly into the upper and now unfilled chamber 16. By the foregoing action, the closure member 6 has been lifted from its seat 4 and the flushing operation now takes place to produce a predetermined volume of water to pass to the fixture. However, when it subsequently becomes necessary to stop the flushing action it is desirable to have it cease gradually in order to avoid disturbance of the siphonic action of the closet bowl. A portion of the incoming flushing water bypasses through the port 17 to the chamber 16 above the plunger 7 and inasmuch as the auxiliary valve 8 has been returned to its seat by the raising of the said plunger and the spring 11, the pressure within the chamber 16 rises to thereby force the plunger 7 and the closure member 6 down to its seat 4. It is unnecessary that the closure member 6 should seat upon the frusto-conical or tapered portion, as indicated. Instead it may seat upon a flat horizontal annular portion of the closure and in such

case a minimum clearance may be maintained between the tapered surface portions of the seat and closure member, respectively, for reasons hereinafter referred to in more detail.

Frequently, in such cases in which the seat or closure member is not tapered, the latter member is provided with an extension of smaller diameter therebelow that passes freely within the seat opening to serve as a throttling lip during the period of time when the plunger is seating. The latter arrangement results in the desirable retarding of the final seating of the closure member sufficiently long enough to provide ample refill of the closet bowl after its siphonic action has ceased. However, it frequently happens that the throttling effect produced results in undesirable noises, probably originating largely from the cavitation due to throttling action.

It is therefore my purpose to momentarily retard the downward travel of the plunger 7 just before the closure member is seated, to provide that when siphonic action through the bowl ceases sufficient refilling will thereafter occur to provide a water seal. It has been found that the novel diaphragm type of valve of my invention permits of the use of the serrated tapered closure member to insure relative quietness in operation, and also assures of an adequate refill of the bowl for the purpose referred to.

The operation of the valve may perhaps be best understood by referring to Figs. 2 to 5 inclusive, especially in considering the sequence of operation with relation to the position of the diaphragm and the plunger. Thus in Fig. 2, with the valve closed the fluid pressure in the chamber 16 is equal to the line pressure and the diaphragm 17 is therefore flexed against the tension of the spring 21, as shown.

With the valve now in open position, as shown in Fig. 3, the flushing operation is taking place and accordingly the pressure in the chamber 16 is reduced to a minimum so that the diaphragm is forced downwardly by the spring 21. In Fig. 4, the valve is still partly open and flushing continues approximately to this position of the closure member, as indicated. At this stage, the chamber 16 is being filled with line fluid and accordingly the fluid pressure in the chamber is increasing. Here the diaphragm is beginning to flex upwardly due to the increase in pressure within the chamber 16, and the refill starts. In Fig. 5, the valve is shown as being slightly open or almost closed. At this stage, flushing has substantially ceased and the refill continues, whereupon the constantly increasing pressure in the chamber 16 has its rate of increase retarded due to the flexing upwardly of the diaphragm 17, as it moves to the final position as shown in Fig. 1 in which the valve is again in seated or closed position. In summary, when the chamber 16 is filling with water the pressure in the chamber increases directly with the entering water as long as the volume remains constant. It is apparent that the spring loaded diaphragm 17 varies the volume of the chamber 16 so that by adjusting the spring tension it is possible to reach a predetermined stage at which the volume increases and the pressure only enough to compress the diaphragm spring. The desired point for retarding the increase in pressure in the chamber 16 is just before the closure member seats, which ends the action of the plunger 7 and allows for proper refill. As the extent of the volume increase of chamber 16 reaches its maximum, pressure increases at a much more rapid rate, and

the final seating of the closure member occurs. The chamber above the diaphragm is vented to the atmosphere at 28 allowing for free movement of the diaphragm whether it be of rubber, metal or even of bellows form.

The use of a bellows 31 having a stop 32 as shown in Fig. 6 provides for more available volume to add to the chamber 16 and thus is adaptable for any size closet bowl. It is also possible to use a corrugated diaphragm to obtain a larger volume control. It is possible to eliminate the spring 21 by removing the vent 28 and utilizing the pneumatic cushion formed in the auxiliary chamber 29 above the diaphragm 17 or bellows 31, but this is not a preferred construction. Other forms of resilient means such as rubber may replace the spring 21, but it is believed that an adjustable spring is preferable as being the more convenient means to handle the necessary amount of refill which varies with different models of bowls. By adjustment of the tension of the spring above the diaphragm it is possible to increase or decrease the amount of refill by temporarily halting the downward travel of the plunger at different stages of valve operation.

A flush valve has thus been obtained which will operate silently and in combination therewith has means for an automatic refill. Numerous details of construction can be varied throughout a wide range and it is intended therefore to be limited only by the claims appended hereto.

I claim:

1. In a flush valve comprising a casing having an inlet and an outlet, a seat in the casing, a plunger having a closure member adapted to reciprocably travel in a chamber above the said seat, an auxiliary valve associated with the said plunger, means on the casing for actuating said auxiliary valve, pressure responsive expansible means in the upper part of the said chamber for jointly varying the volume thereof and the rate of pressure increase to cause retarding of the downward movement of the plunger.

2. A flush valve comprising a housing having an inlet and an outlet, a seat in the housing separating the inlet from the outlet, a plunger in the housing reciprocably movable in a chamber above the said seat, the said plunger comprising an auxiliary valve and a closure member, means for actuating the said auxiliary valve whereupon when the handle is actuated the plunger rises from the seat, bypass means from the inlet to the upper chamber, a spring loaded flexible member providing a variable volume for the chamber, whereby fluid entering the bypass means effects a rapid rate of pressure increase in the upper chamber until the initial tension in the said spring is overcome, the pressure increasing at a reduced rate until the maximum volume is attained under full compression of the spring.

3. A flush valve comprising a casing having an inlet and an outlet, a valve seat between the inlet and the outlet, a piston valve reciprocably movable within the casing and cooperating with the seat to control the flow of water between the inlet and the outlet, a pilot valve carried by the said piston valve, actuating means for the said pilot valve, the casing having a chamber above the said piston valve, bypass means through the said piston valve, a resiliently loaded diaphragm in the upper portion of said chamber, whereby when the piston valve is seating by normally increasing pressure in the said chamber, the pressure rise is automatically retarded as the volume of the said chamber increases by the compression

of the resiliently loaded diaphragm, whereupon the piston valve is temporarily retarded in its closing movement until such time as the volume of the said chamber reaches its maximum and pressure therewithin increases at a more rapid rate forcing the piston valve closed.

4. A flush valve comprising a casing having inlet and outlet ports, an operating handle cooperating with the casing, a main valve for allowing the flow of water therethrough, an auxiliary valve associated with the operating handle for initiating the operation of the main valve, a closure member on the main valve for cooperation with a seat in the said casing, the main valve having a chamber thereabove for upward movement of the main valve upon release of fluid pressure in this chamber by opening of the said auxiliary valve, a resiliently loaded diaphragm in the upper portion of the said chamber, whereby when the main valve is seated by increasing the pressure of fluid in the said chamber the volume of the chamber increases by a flexing of the diaphragm to a concave form and the pressure increase is retarded until the volume again remains constant whereupon the main valve which was temporarily retarded by the retarded rate of pressure increase is moved to a full seating position.

5. A flush valve comprising a casing having an inlet and an outlet, a valve seat between the inlet and the outlet, a piston valve reciprocably movable within the casing and cooperating with the seat to control the flow of water between the inlet and the outlet, a pilot valve carried by the said piston valve, actuating means for the said pilot valve, the casing having a chamber above the said piston valve, bypass means

- through the said piston valve, a resiliently loaded diaphragm in the upper portion of said chamber, whereby when the piston valve is seating by normally increasing pressure in the said chamber, 5 the pressure rise is automatically retarded as the volume of the said chamber increases by the compression of the resiliently loaded diaphragm, whereupon the piston valve is temporarily retarded in its closing movement until such time as the volume of the said chamber reaches its maximum and pressure therewithin again increases at its normal rate forcing the piston valve closed, a cover for the diaphragm having means communicating with the atmosphere.
- 10 6. A flush valve comprising a housing having an inlet and an outlet, a seat in the housing separating the inlet from the outlet, a plunger in the housing reciprocably movable in a chamber above the said seat, the said plunger comprising an auxiliary valve and a closure member, means for actuating the said auxiliary valve whereupon when the handle is actuated the plunger rises from the seat, bypass means from the inlet to the upper chamber, a flexible spring 15 20 loaded diaphragm in the upper chamber, whereby fluid entering said chamber through the bypass means creates a hydrostatic pressure which increases at a constant rate of speed until the pressure exceeds the spring tension, the flexible diaphragm assuming a concave form, the volume of the chamber being increased as the pressure in the chamber increases whereby the seating of the plunger is retarded, enclosure means for clamping the said diaphragm to the 25 30 35 said housing.
